UNITED STATES PATENT OFFICE.

JAMES WILKINSON, OF BIRMINGHAM, ALABAMA, ASSIGNOR TO THE WILKINSON STEAM TURBINE COMPANY, OF BIRMINGHAM, ALABAMA, A CORPORATION OF ALABAMA.

HIGH-SPEED INERTIA-GOVERNOR.

SPECIFICATION forming part of Letters Patent No. 769,284, dated September 6, 1904.

Application filed May 2, 1904. Serial No. 205,993. (No model.)

To all whom it may concern:

Be it known that I, JAMES WILKINSON, a citizen of the United States, residing at Birmingham, in the county of Jefferson and State of Alabama, have invented new and useful Improvements in High-Speed Inertia-Governors, of which the following is a specification.

My invention relates to speed-governors of the inertia type designed to provide a wide range of movement for its controller parts, combined with great sensitiveness to variations in the speed of shaft rotation.

My governor is particularly adapted for controlling elastic-fluid turbines where the efficiency and economy in operation are directly dependent on the accuracy with which the motor-fluid supply is proportioned to the load. If the turbine have a large number of independent valves whose operation in rapid succession may be desired, the governor must be capable of considerable adjustability without detriment to its sensitiveness. My present invention comprises these characteristics and is preferably embodied in the construction and arrangement of parts hereinafter described and claimed, and illustrated in the accompanying drawings, in which—

Figure 1 is a top plan view of my governor. Fig. 2 is a side elevation, partly in section, to illustrate the manner of mounting and connecting the several parts. Fig. 3 illustrates the governor-weights in their open position and a modification by which the inertia effect of the coiled spring is dispensed with. Fig. 4 is an end view of Fig. 3. Fig. 5 is a detail view of the end of the governor-shaft. Figs. 6 and 7 are detail views of the toothed plate mounted on the shaft. Fig. 8 is a top plan view of the double spindle for the governor-weights, showing the antifriction-rollers in a suitable raceway. Fig. 9 is a vertical section through Fig. 8 and shows the grooved washer forming part of a ball-raceway. Fig. 10 is a detail view, broken away, of the sliding collar; and Figs. 11 and 12, respectively, represent longitudinal and transverse sections through the collar to show the roller-guides therefor.

Similar reference characters refer to the same parts throughout.

I have illustrated my invention applied to a shaft 1, which may form part of or be driven by the main turbine-shaft or the shaft of any type of engine. This shaft is preferably reduced to form a portion 2, which is provided with screw-threads 3 near its inner end and at its outer end is formed with a square shank 4 and cylindrical stud 5, both integral therewith and the latter threaded at its outer end. A circular beveled cap-plate 6, having a square central opening, slips over stud 5 and is forced over shank 4, which holds it rigid with the shaft. This plate is preferably of equal diameter with the shaft 2 and of a thickness equal to the length of shank 4 and is provided on opposite sides of its beveled face with teeth, forming segmental gears 7 and 8. A sleeve 9 is provided with oppositely-disposed integral arms 10 and 11, which extend at right angles therefrom and are threaded at their outer ends. The sleeve surrounds stud 5 and forms a raceway for the series of antifriction-rollers 12, interposed between it and the stud, and at its outer end is grooved at 13 to form a raceway 14, with a correspondingly-grooved washer 15, which is held in position by the nut 16 and jam-nut 17, mounted on the outer end of stud 5. Balls 18 are placed in the raceway 14 and relieve the friction which would otherwise occur between the rotary nut 16 and the several normally stationary parts which it holds in position on the shaft. The governor-weights 19 and 20 are each provided with enlarged hollow outer ends and relatively smaller inner portions, which are respectively provided with circular lugs or ears 21 and 22. The lug 21 has a central opening in which a steel bushing 23 is inserted, which forms a raceway for antifriction-rollers 24 therein and surrounding arm 10 of sleeve 9, to which the weight 19 is pivotally connected. The weight 20 is pivotally connected in a similar manner to arm 11, and washers 25 and nuts 26 prevent the disengagement of the weights from their respective axes. Viewing the weights as shown

in their closed position, Fig. 2, it will be noted that lugs 21 and 22 are respectively provided with segmental sets of gear-teeth 27 and 28, which are disposed on opposite sides of a horizontal plane between the faces of the weights. These gear-teeth mesh, respectively, with gears 7 and 8 on cap-plate 6, which moves with the shaft and are held firmly in engagement therewith by nut 16 and washer 15 through the antifriction-balls 18, which engage sleeve 9. Relative movement between plate 6 and sleeve 9 will cause the weights to swing on their pivots for the purposes hereinafter described.

15 A nut 29 and jam-nut 29^a engage the threads 3 on shaft 2, and at its outer end nut 29 is provided with an annular groove which with a corresponding groove in a washer 30 forms a raceway for antifriction-balls 31. Washer 30 surrounds shaft 2 without engaging it and forms an inner bearing for the spiral spring 32, also surrounding the shaft and at its outer end bearing against a guide-collar 33 of the main transmission-frame 34. This frame at 25 its outer end has arms or extensions 35 provided each with lugs 36 and a semicircular groove 37. Spindles 38 pass through said pairs of lugs and are locked to bosses 39, integral with said lugs, by pins 40. Loose shells 30 41 are rotatably mounted on antifriction-rollers 42, surrounding these spindles, and are disposed between lugs 36, which extend sufficiently beyond the shells to form side guides for the curved guides 43 on the governor-35 weights, against which the frame is normally pressed by spring 32. At its inner end the transmission-frame has a ball-bearing connection with a sliding collar 44, mounted on shaft 1. This connection comprises an enlarged portion 45, integral with the bars 46, which connect to arms 35 and are disposed without the spring 32. I insert a ball-race 47 in portion 45 and screw-thread the latter at 48 to receive a second ball-race 49, which is 40 locked against displacement by a screw 50 and serves to hold the race 47 in position. A double cone 51 is screwed onto the outer end of sliding collar 44 and locked by a set-screw 55, and two sets of antifriction-balls 56 and 57 45 move in the two races thus provided and take up all the friction of rotation between the frame 34 and collar 44. When the former is rotated by the gears 7, 8, 27, and 28, collar 44 is prevented from rotation by two oppositely-disposed rows of antifriction-sleeves 58, 50 mounted on studs 59, screwed into the shaft 1, as shown in Fig. 12. The collar is provided with longitudinal grooves 60 in its inner face, in which the studs are disposed and 60 against the sides of which the sleeves 58 bear. The sliding collar 44 has two annular flanges 61 and 62, between which the split slip-collar 63 is mounted and provided with perforated lugs 64, by which the two halves are bolted together. An oil-ring 65 rides on the sliding col-

lar between flange 61 and the inner end of portion 45 of the transmission-frame and dips into any suitable oil-reservoir, as 66. From this oil-receiving portion of the sliding collar oil-ducts 67 and 68 lead under flange 61 and supply lubricant to the slip-collar 63. Ducts 67 continue up the inner face of flange 62, as seen in Fig. 2, and ducts 68 stop short of flange 62 and connect with grooves in the inner face of flange 61, as seen in Fig. 11. The weight of ring 65 as it rotates with the sliding collar forces oil into the ducts, so that in a simple and comparatively inexpensive manner I am enabled to apply a forced lubrication to the slip-collar 63 to reduce to a minimum the friction on the antifriction-sleeves 58 and studs 59. As will be noted in Fig. 10, the supply-ports for the oil-ducts are of less width than the oil-ring, which is shown in dotted lines, and thus the oil under the ring after entering these inlet-openings will be forced to pass under flanges 61. Stud-bearings 69 are secured to or formed integral with the slip-collar 63, and these studs may be connected in any suitable manner to the controller mechanism for the fluid-supply to a turbine or motor. This controller mechanism, which may be a valve or means to control the operation of valves, is adapted to admit the full supply of motor fluid when the governor-weights are closed, as shown in Fig. 1, and the slip-collar shifted with collar 44 and the transmission-frame 34 to its extreme outer position. This represents its full-load position, when the speed of rotation will be lowest. As the speed increases under a decreasing load the weights will move outwardly and shift the slip-collar, with the frame 34 and collar 44, inwardly, in which positions the controller mechanism will reduce or cut off the supply of fluid, which will thus be automatically proportioned to the load.

In Fig. 3 I show a modified form of my invention, in which the washer 30 and antifriction-balls 31 are transferred to the outer end of the spring. Here I provide two oppositely-grooved washers 70 and 71, which form a raceway for balls 72 between them. The spring 32 will then bear against the nut 29 and washer 70 and will therefore have no tendency to move or rotate with the governor parts independently of the shaft's movement. In this construction the inertia effect of the spring is dispensed with.

In describing the operation of my inertia-governor I will first refer to Fig. 2, in which the several parts are shown in the position they occupy before shaft 2 commences to rotate and in which the motor-valves will be open to admit a full supply of fluid-pressure. As shaft 2 commences to rotate in the direction of the arrow the segmental gears 7 and 8 will engage the gears 27 and 28 on the governor-weights, these gears being held in mesh in the manner hereinbefore described. This engagement of

the gears will act to move the shell 9, on which the weights are pivotally mounted, around the spindle 5 and at the same time will tend to swing the weights outwardly on their axes 10 and 11. The springs 32 by pressing the anti-friction-shells 41 against the weights would counteract their tendency to swing open, due to centrifugal power and to the action of the gears. Since the curved guides 43 on the governor-weights engage their side guides formed by the lugs 36 on the transmission-frame, the latter will also be rotated. As the speed increases the weights will move outwardly on the curve *a a*, Fig. 4, as a result of their combined swinging and pivotal movement, and as they move outwardly their curved guides 43 will by engaging anti-friction-shells 41 move frame 34 inwardly and shift the sliding collar 44. During a constant speed there will be no relative movement between the shaft and governor parts, as they will then be moving together; but if the shaft speed increase or diminish the tendency of the inertia of the governor parts will be to cause them to endeavor to continue moving at the same speed of rotation. The relative movement between the shaft and governor parts resulting from the inertia movement will take effect through the segmental gears to swing the governor-weights, and therefore shift the transmission-frame. During an increasing shaft speed the governor parts will assume a position partly due to the centrifugal motion of the weights and partly to the lag of the parts caused by their own inertia. Conversely, during a decreasing speed the inertia of the parts will cause them to take a position slightly in the lead of the normal position they would have during a continuous speed, which inertia effect, in addition to the centrifugal action, adds to the governor's sensitiveness. The effect, therefore, of an increasing shaft speed above that of the governor parts will be to swing the governor-weights more widely open, and, conversely, if the shaft speed decrease the gears will act to swing toward each other. From this arrangement it follows that the governor-weights will not only move in direct response to the centrifugal power derived from the shaft rotation, but will have their delicacy of adjustment increased by the gear connection with the shaft, which acts to swing them in one or the other direction upon each variation in the speed of rotation of the shaft.

55 The antifriction-shells 41 reduce the friction of the governor-weights in moving the transmission-frame, and the antifriction-balls 31 reduce the friction between the nut 29 and spring 32, which also shifts with the transmission-frame when it is rocked by the inertia movements of the governor-weights. The rollers 58 reduce the friction of the sliding collar 44, and the other antifriction-bearings coöperate to reduce to a minimum the friction which it is necessary for the governor to

overcome in operating the means to vary the supply of motor fluid.

In many cases it is not necessary that the governor should be so sensitive, and in applying my invention to engines of this character I will dispense with the gear connection between the shaft and the governor-weights and will mount the pivotal bearing for the weights rigidly on the shaft. In this arrangement the governor will respond to the centrifugal effect only of the shaft movement, but will embody the improvements in construction and arrangement hereinbefore described.

The gear connection between the governor-weights and shaft may be of any desired construction, and a link may be used to connect the governor-weights to the transmission-frame. The other features of construction may be modified without departing from the spirit of my invention, for which reason I do not desire to limit myself to the details of construction.

Having thus described my invention, what I claim as new, and desire to secure by Letters Patent, is—

1. In a speed-governor, the combination with a rotatable shaft, of a centrifugal governor-weight movably connected thereto and adapted to rotate therewith, spring means opposing the centrifugal action of said weight, and means to directly transmit to said governor-weight movements of said shaft relatively thereto which are due to changes in the speed of the shaft's rotation.

2. In a speed-governor, the combination with a rotatable shaft, of a spring-loaded centrifugal governor deriving its rotary motion therefrom, means to utilize a relative movement between the rotating parts to shift the governor, and a controller device shifted longitudinally by said governor.

3. In a speed-governor, the combination with a rotatable shaft, of a pivoted governor-weight adapted to be rotated by said shaft, a positive connection between said shaft and weight which effects a swinging movement of the latter when the speed of shaft rotation changes, spring means to counteract the centrifugal force of the weight, and a slip-joint between said spring means to one of the parts against which it bears.

4. In a speed-governor, the combination of a rotatable shaft, a centrifugal spring-loaded governor rotatable therewith and comprising one or more weighted arms, means to cause said arm or arms to rotate with said shaft, means connected to said shaft to cause the inertia of said arm or arms to automatically shift it or them whenever the shaft speed changes, a controller device moved by said governor and means to prevent the transmission of the shifting movements of said arm or arms due to the inertia to said collar.

5. In a speed-governor, a rotatable shaft,

- 4
- 5 pivoted governor-weights driven thereby, a connection between the shaft and said weights which causes them to rotate with the shaft and utilizes their inertia to swing them open or closed as the speed of shaft rotation varies, a controller device actuated by said governor, and means to restrict said device to longitudinal movement.
6. In a speed-governor, a rotatable shaft, a rotary element driven by said shaft and capable of a limited oscillatory movement, centrifugal weights carried by said element, and an element moved by said weights and adapted to control the fluid-supply to a motor.
- 10 7. In a speed-governor, a rotatable shaft, a bearing-sleeve mounted loosely thereon, centrifugal weights pivotally mounted on said sleeve and at their inner ends engaging said shaft which, by this connection, causes the sleeve to rotate with it under constant speeds of rotation and permits the sleeve to rock sensitive to the effect of its inertia under varying speeds, and means to cause said inertia movements of said sleeve to swing the weights
- 15 20 25 on their pivots.
8. In a speed-governor, the combination with a rotatable shaft, of a rotatable element, a spring-loaded centrifugal weight mounted thereon, and a driving connection between said shaft and element which causes the latter to act by its momentum and that of said spring-loaded weight to shift said weight.
- 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920
13. In a speed-governor, a rotatable driving element, a driven element comprising a body portion, rotatable in the same direction with said driving element, and a centrifugal weight pivotally mounted thereon, a connection between said driving element and said weight which causes said body portion to rotate with said driving element and has a tendency to swing said weight on its pivot, and spring means to oppose said pivotal movement.
14. In a speed-governor, a rotatable shaft, a driven element comprising a rocking body and a pivoted weighted arm mounted thereon, and a driving connection between said shaft and arm which causes said element to rotate and rocks said body when the speed of shaft rotation varies.
15. In a speed-governor, a rotatable shaft, centrifugal weights, a support for said weights and a driving connection from said shaft which permits said support to shift and adds the inertia force of the weights to their centrifugal action, and controller devices which move in correspondence with said weights.
16. In a speed-governor, a rotatable shaft, an element rotatably mounted on said shaft and rotatable therewith, centrifugal weights mounted on said element, and a connection between said weights and the shaft by which the inertia of the weights, upon changes in the speed of shaft rotation, acts to shift their position.
17. In a speed-governor, a rotatable shaft provided with gear-teeth at one end, a driven element, a centrifugal weight pivoted to said element, a gear connected to said weight and meshing with the teeth on said shaft, and constituting the driving connection for said element, and spring means to counteract the tendency of said gears to swing the weight outwardly.
18. In a speed-governor, a rotatable shaft, a rocking support for centrifugal weights, a gear connection between said shaft and said centrifugal weights which acts both to shift said weights and cause them to rotate responsive to the movement of said shaft, and spring-pressed means to oppose the outward movements of said weights.
19. In a speed-governor, a rotatable shaft, segmental gears at its outer end, pivoted centrifugal weights, a rocking support therefor which normally rotates with said shaft, segmental gears connected one to an end of each weight and meshing with a gear on said shaft, and spring means to oppose the tendency of said meshing gears to swing the weights outwardly.
20. In a speed-governor, a rotatable shaft reduced at one end to form a spindle, a sleeve mounted on said spindle and provided with one or more spindles projecting from its side,

5 a centrifugal weight-arm pivotally mounted on each of said latter spindles, a segmental gear on the inner end of each weight-arm, gear-teeth carried by said shaft, means to hold said gears in engagement and means to oppose the tendency of said gears, while transmitting motion from the driving to the driven parts, to swing said weighted arms on their pivots.

10 21. In a speed-governor, a driving-shaft having a square shank and a circular spindle at one end, a circular plate provided with gear-teeth and rigidly mounted on said shank, a driven element rotatably mounted on said spindle, centrifugal weights pivotally connected to said element and provided with segmental gears at their inner ends, means to hold said gears in mesh, and means to limit their meshing movement and also to oppose 15 the resulting tendency of the weights to swing on their pivots.

20 22. In a speed-governor, a driving-shaft, a toothed plate mounted thereon, an element driven thereby, gear connections between said element and plate whereby the former is rotated, and pivoted rotating weights whose inertia power acts through said gears to coöperate with their centrifugal power in swinging them on their pivots, and means to regulate 25 the movements of the weights and transmit them to controller devices.

25 23. In a speed-governor, a rotatable shaft, a combined centrifugal and inertia governor driven thereby, and a transmission-frame between said governor and a controller device, said frame being rotatable with and driven by said governor so that it adds its inertia effect to that of the governor.

30 24. In a speed-governor, a rotatable shaft, centrifugal governor-weights driven thereby, a transmission-frame, an antifriction connection between said weights and frame, a sliding collar, an antifriction connection between said frame and collar, and a slip-collar on said 35 45 sliding collar.

50 25. In a speed-governor, a rotatable shaft, centrifugal governor-weights driven thereby, a curved guide on the outer side of each of said weights, a sliding transmission-frame, antifriction-rolls at one end which engage 55 said guides on the weights, a connection between said frame and weights whereby they rotate together, and adjustable spring means to press said frame against said weights.

55 26. In a speed-governor, a rotatable shaft, centrifugal governor-weights mounted thereon, a sliding spring-pressed transmission-frame which engages said weights and which is shifted as the weights move, guides on said 60 frame which engage said weights and cause the frame to rotate with them, and antifriction-rollers between said guides.

65 27. In an engine-governor comprising a rotary element having centrifugal weights mounted thereon, a driving connection be-

tween the rotary element and a moving shaft which permits said element to have a limited rotary movement, means to utilize said rotary movement to shift the centrifugal weights, and a controller element to supply the motor fluid to the engine which is shifted by said weights.

70 28. In an engine-governor, a rotating element, a driving-shaft for said element on which it is mounted, centrifugal weights mounted on said element, a driving connection between said shaft and element which rocks the latter when the speed of shaft rotation varies, means to transmit the effect of this rocking movement to the centrifugal inertia-weights and means shifted by said weights which control the supply of fluid to a motor.

75 29. In an engine-governor, a rotatable shaft, a bearing-sleeve loosely mounted thereon, centrifugal weights pivoted to said sleeve, a gear connection between said weights and shaft which tends to move the weights in one direction and to rotate the sleeve, and spring means to oppose the swinging movements of the weights effected by said gears, and means to transmit the movement of said weights to a controller device.

80 30. In an engine-governor, a rotating shaft carrying segmental gears at one end, an oscillatory element mounted on said shaft and rotatable therewith, one or more governor-weights pivoted to said element and provided with segmental gear or gears which are engaged by the gears on said shaft and upon 85 relative movement between the shaft and said element cause the weight or weights to move on their axis or axes, spring-pressed means to oppose the swinging movement of the weights and means to transmit the movement of the 90 governor-weights to controller means.

95 31. In a speed-governor, the combination with a driving-shaft and centrifugal weights, of a support for said weights mounted so as to be capable of an oscillatory movement on 100 a bearing, and connections between said centrifugal weights and said shaft whereby the support is rotated and the weights are shifted by their own inertia when the speed of shaft rotation changes.

105 32. In a speed-governor, a rotatable shaft, centrifugal weights rotatably mounted on an end of said shaft, a driving connection between said shaft and weights which swings the latter in one or the other direction and causes 110 them to rotate with said shaft, and a spring-pressed frame engaging said weights and shifted longitudinally by their opening movement, and a slip-collar for connection to the fluid-controlling means which is shifted by 115 said frame.

120 33. In an engine-governor, a rotatable shaft, centrifugal weights connected to an end of said shaft, a transmission-frame having an anti-friction-surface which engages said weights, 125

a coiled spring pressing said frame against said weights to close them and adjustable anti-friction-bearings for said spring mounted on said shaft, a sliding collar moved by said frame, and antifriction-bearings therefor.

34. In a centrifugal governor, the combination of a driving-shaft, a sliding collar, means to transmit the governor's motion to said collar, a longitudinal groove or grooves in the inner wall of said collar, and antifriction-rollers connected to the support for said collar and engaging the said walls of said groove or grooves for the purposes described.

35. The combination of centrifugal governor-weights which are moved by their own inertia, a sliding collar mounted on the driving-shaft for said governor, means transmitting the governor's movements to said collar, antifriction-bearings between said means and collar, and antifriction-rollers mounted on said shaft and engaging longitudinal grooves in said collar to restrict it to longitudinal movement.

36. The combination with a driving-shaft of a centrifugal inertia-governor driven thereby, a collar mounted on said shaft and actuated by said governor and antifriction devices mounted on said shaft and engaging said collar to prevent its rotation on said shaft.

37. The combination with a driving-shaft of a centrifugal inertia-governor driven thereby, a collar mounted on said shaft, a device for transmitting the governor's movement to said collar, antifriction-bearings between said device and the governor and collar, a coiled spring engaging said device and tending to hold the governor in its closed position, and antifriction-bearings upon which said spring is mounted.

38. In a centrifugal speed-governor, the combination therewith of a rotatable shaft, a controller device mounted thereon and shifted by said governor, and antifriction means to restrict said device to longitudinal movement on said shaft.

39. In an inertia-governor, the combination of a rotatable shaft, a sliding collar, means to

transmit the governor's motion to said collar, and antifriction means to restrict said collar to longitudinal movement upon its bearing. 50

40. In an inertia-governor, the combination of a rotatable shaft, inertia-shifted governor-weights, a movable collar mounted thereon and adapted to operate fluid-pressure-controlling means, means to prevent the rotation of said sleeve on said shaft, and means to transmit the governor's motion to said collar. 55

41. In a combined centrifugal and inertia governor, the combination of a governor-shifted controller device, a slip-joint between said governor and said device, means to support said device and means to restrict it to longitudinal movement upon its supporting means. 60

42. In a speed-governor, a rotatable shaft, centrifugal inertia governor-weights driven thereby, a sliding controller-collar, means to transmit the movement of the governor-weights to said collar, and an antifriction connection between said means and collar. 65

43. In a combined centrifugal and inertia governor, the combination therewith of a shaft, a controller-collar mounted on said shaft, antifriction means to restrict said collar to longitudinal movement on said shaft, a fluid-pressure-controlling means actuated by said collar, means to connect said collar to the governor and an antifriction-joint between said collar and said means. 70

44. In a speed-governor, a rotatable shaft, an element rotatably mounted on said shaft and rotatable therewith, centrifugal weights mounted on said element, and a toothed-gear connection between said weights and the shaft by which the inertia of the weights, upon 85 changes in the speed of shaft rotation, acts to shift their position.

In testimony whereof I have signed my name to this specification in the presence of two subscribing witnesses.

JAMES WILKINSON.
